Edward Orton

UNITED STATES PATENT OFFICE.

MARIA A. WILSON, OF GRAYSON, CALIFORNIA.

COMBINED SEWING IMPLEMENT.

SPECIFICATION forming part of Letters Patent No. 269,610, dated December 26, 1882.

Application filed May 5, 1882. (No model.)

To all whom it may concern:

Be it known that I, MARIA A. WILSON, of Grayson, in the county of Stanislaus and State of California, have made and invented a new and useful Holder for Spools and Balls of Thread and Sewing Implements; and I do hereby declare that the following is a full, clear, and exact description of the same, reference, being had to the accompanying drawings.

10 My invention has for its object to provide a simple and handy device for the use of needle-women to be attached to the clothing or about the person of the user, and adapted to hold sewing-implements, and to receive and support 15 thread, silk, or yarn, whether in the form of balls or upon spools in such manner that the desired quantity may be drawn off as required for work.

It consists of a light frame having a fastening-pin or means for attaching the device to the person, and formed or provided with a reel or spool-holder from which the thread can be drawn off, a socket to hold a thimble, and a cushion or receptacle for pins and needles.

25 It consists also in the combination, with the spool-holder, of a detachable cage or receptacle to hold and confine a ball of thread or yarn, by which the device may be made to receive and hold in a position for convenient use either 30 a spool or a ball of material.

Referring to the accompanying drawings, Figure 1 shows the device ready for use with the ball-holder attached. Fig. 2 shows the frame as constructed of a single piece of wire. 35 Fig. 3 shows the general construction of the ball-holding cage. Fig. 4 shows the form and manner of using the spool-holder when the cage is detached.

The device consists of a light wire frame 40 formed by bending a length of wire, A, around a mandrel, so as to form in the center portion a spring-coil, b, and then by bending down the two ends of the wire toward each other to form the two jaws A A. The end portions, a a, of 45 these parts being bent into a rectangular shape, the ends are carried in toward each other to be substantially in line together when the jaws A A are allowed to close. This lower or end portion of the frame thus constitutes a reel and 50 holder for a spool.

Upon one of the members A I form a loop,

C, to receive a thimble, and upon the other one A a similar loop, d, in which I fix a cushion for pins and needles, and at the point of junction of the jaws where the spring b is located 55 I fix a fastening-pin, E, for securing the device to the clothing of the user.

In connection with the spool-holder I provide a cage, F, to contain and hold a ball of thread or yarn, so that the device is of service both 60 where the thread or other material used is supplied on spools, and where it is in the form of balls. This cage F is made of two parts or halves, so that it is readily opened and separated to admit the ball. It is attached and secured to the jaws A, and in the rectangular frame or reel by means of small clips or spring-jaws g g, which engage with the wires a a, and by loops or eyes h h, through which the ends of the spool-holder are passed when the cage 70 is fixed in place.

The two parts of the cage are formed in a very simple manner by securing curved wires f f in a radial position across a circular rim or ring, i, as shown in Fig. 3 of the drawings, the 75 two rings, when closed together, forming a spherical cage. A hinge or link, j, connecting the two rings together at the top, serves to prevent the parts being separated and lost when they are removed from the frame, and a locking-catch can be employed to keep the two halves shut together, if it be necessary.

In using my device the spool of material is placed in the reel by spreading apart the jaws A A and inserting the ends of the wires in the 85 apertures in the head of the spool, and then allowing the jaws to spring together. The end of the thread is then carried up and passed through the eye at the top of the frame formed by the spring b, and the device is attached to 90 the breast of the user by means of the fastening-pin. If a ball of thread, yarn, or crochet-cotton is to be held, the jaws are spread apart as before, and the cage F is fixed in place, one-half on each side, and the ball being then put in 95 place the cage is closed together around it, and retained in this position by the action of the spring, or by a catch, if one is provided.

Having thus fully described my invention, what I claim, and desire to secure by Letters 100 Patent, is—

1. A device for holding spool-thread and

sewing implements for the use of needle-women, consisting of the two jaws A A, connected together by a spring-joint, b, the rings or loops C d, and the rectangular spool reel or holder on the end, in combination with a fastening for attaching the device to the person, all constructed and combined together substantially as specified.

2. In combination with the jaws A A, the detachable and removable ball-holding cage F, 10 constructed for application and use, substantially as specified.

MARIA A. WILSON. [L. S.]
